(57) **CLAIM**

The ornamental design for an area lighting fixture, as shown and described.

DESCRIPTION

FIG. 1 is a front view of an area lighting fixture showing the new design;

FIG. 2 is a left side view of the area lighting fixture shown in FIG. 1;

FIG. 3 is a right side view of the area lighting fixture shown in FIG. 1;

FIG. 4 is a rear view of the area lighting fixture shown in FIG. 1;

FIG. 5 is a top view of the area lighting fixture shown in FIG. 1;

FIG. 6 is a bottom view of the area lighting fixture shown in FIG. 1; and,

FIG. 7 is a perspective view of the area lighting fixture shown in FIG. 1.

Features shown in dash lines are provided for illustrative purposes and do not form part of the claimed design.

1 Claim, 4 Drawing Sheets
